UNITED STATES PATENT OFFICE.

THEODORE S. WILKIN, OF MILWAUKEE, WISCONSIN.

SPLICER-BAR FOR RAIL-JOINTS.

SPECIFICATION forming part of Letters Patent No. 394,629, dated December 18, 1888.

Application filed April 5, 1888. Serial No. 269,738. (No model.)

To all whom it may concern:

Be it known that I, THEODORE S. WILKIN, of Milwaukee, in the county of Milwaukee and State of Wisconsin, have invented certain new and useful Improvements in Splice-Bars for Rail-Joints, of which the following is a specification.

My invention relates to rail-joints, and has reference more particularly to a novel construction of the fish-plates, all as hereinafter set forth, whereby the nuts are prevented from becoming loosened.

In the drawings, Figure 1 is a horizontal sectional view through a rail-joint, showing the invention in its simplest form; and Figs. 2, 3, and 4, views illustrating slightly-different arrangements of the joint.

A A indicate the rails, which may be of any suitable construction; B B, the fish-plates; and C C, bolts passing transversely through the rails and plates and provided with nuts D, as shown in all the figures.

As shown in Fig. 1, one of the fish-plates is provided at or near each hole through which the bolts pass with one or more spring-arms, E, which project outward slightly away from the face of the plate and bear against the inner face of the bolt-head, nut, or washer, as the case may be. These arms E E may be 30 and preferably are formed at the same time and by the same operation with the punching of the holes, and hence require no extra work or handling in their manufacture. The arms are formed by cutting two slots in the plate 35 adjacent to and intersecting or terminating in the hole for the bolt, so that when the arms are bent outward, as shown, the free ends will engage the bolt-head or nut. After the nut is screwed up upon the bolt the nut 40 is prevented from turning by reason of the elasticity or spring action of the arms, which bear upon the inner face of the nut with sufficient force to prevent its turning or unscrewing.

45 In Fig. 1 I have shown only one of the bars provided with the spring-arms, while in Figs. 2 and 3 both plates or bars are provided with them.

If desired, the ordinary fish-plates may be 50 employed, and a supplemental plate con-

structed in accordance with my invention be used in addition, as clearly shown in Fig. 4.

A splice-plate having the arms made separate therefrom but riveted or otherwise secured rigidly thereto is within the scope of 55 my invention, which consists, broadly, in a splice-plate having the spring-arms arranged to operate substantially in the manner herein indicated.

I desire to state that I am aware that prior 60 to my invention it has been proposed to employ in connection with the ordinary form of rail-joints spring-washers, which were placed beneath the head of the bolt or the nut; and I am also aware that it has been proposed to 65 provide these washers with lips or spurs, and to these different plans I make no claim. In my plan these special nut-retaining devices are dispensed with, the splice-bar itself being provided with an arm or arms to bear against 70 the under side or face of the bolt-head or the nut.

I am further aware that it has been proposed to employ in a rail-joint two elastic plates (without arms) doubled upon themselves, one on each side of the rails, and to 75 pass bolts through the rails and plates, and such a construction I also disclaim.

Having thus described my invention, what I claim is—

1. A splice-plate provided with a hole (or holes) to receive a bolt, and with a projecting spring-arm to bear upon the inner face of the bolt-head or nut.
2. A splice-plate provided with a hole (or holes) to receive a bolt, and with a projecting spring-arm formed integral with the plate to bear upon the inner face of the bolt-head or nut.
3. A splice-plate provided with a hole (or holes) to receive a bolt, and with a spring-arm having its free end adjacent to the hole, as and for the purpose set forth.
4. A splice-plate provided with a hole to receive a bolt, and with slots intersecting the hole so as to form a spring-arm.
5. A splice-plate provided with a series of holes to receive bolts, and with a series of outwardly-projecting spring-arms adjacent to the bolts.

6. The combination, with rails A A, of splice-
plates, as B B, on opposite sides of the rails,
and bolts C, passing through the rails and
plates, one or both of the plates being pro-
5 vided with projecting spring - arms to bear
upon the inner faces of the bolt - heads or
nuts.

In witness whereof I hereunto set my hand
in the presence of two witnesses.

THEODORE S. WILKIN.
